(57) **CLAIM**

The ornamental design for a case for electronic communication device, as shown and described.

DESCRIPTION

FIG. 1 is a perspective view of a case for electronic communication device showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a case for electronic communication device where a kickstand is in an open position;

FIG. 10 is another perspective view thereof; and,

FIG. 11 is a perspective view of the case for electronic communication device where the case for electronic communication device is in a configuration of use.

The broken lines, and unshaded surfaces bound by broken lines, in all figures which depict portions of the case for electronic communication device represent features that form no part of the claimed design. The broken lines representing a communication device and charging attachment or mount in FIG. 11 represent environment included for the purpose of demonstrating usage and form no part of the claimed design.
